ICE CREAM FREEZER

Thomas Carvel, Winding Road Farms, Chauncey, N.Y.

Filed Apr. 30, 1965, Ser. No. 85,033

Term of patent 14 years

(Cl. D67—2)

FIG. 1

FIG. 1 is a side perspective view of an ice cream freezer, showing my new design.

FIG. 2 is a rear view thereof it being understood that the metal mesh fragmentarily shown is continued through the area indicated, and

FIG. 3 is a top plan view thereof.

The side not shown in the drawing is substantially a mirror image of that shown in FIG. 1.

I claim:

The ornamental design for an ice cream freezer, as shown and described.
